UNITED STATES PATENT OFFICE.

JOHN C. BUGH, OF COLUMBUS, OHIO.

DESIGN FOR A SOAP-DISH.

SPECIFICATION forming part of Design No. 22,705, dated August 15, 1893.

Application filed July 10, 1893. Serial No. 480,095. Term of patent 7 years.

To all whom it may concern:

Beit known that I, JOHN C. BUGH, a citizen of the United States, residing at Columbus, in the county of Franklin and State of Ohio, have invented and produced a certain new and original Design for Soap Dishes or Brackets, of which the following is a specification.

Figure 1 is a view in perspective of my newly designed soap bracket and Fig. 2 is a rear elevation of the same, these two views being deemed necessary to fully illustrate my design.

The leading features of my design consist in a substantially shell shaped cup which projects outwardly at right angles from the face of an oval backing piece, which is provided with a scalloped or fluted edge or periphery. *a* represents a substantially shell shaped

cup the bottom of which is provided with elongated scallops or recesses *b*, said scallop depressions being separated by ribs or ridges *c* which radiate from a point at the center of the back of said cup and extend to the innermost point of the scalloped forward edge of said cup. The backing piece *d*, the contour of which is substantially oval, is provided with a scalloped or fluted periphery or edge as indicated at *d'*.

What I claim, and desire to secure by Letters Patent, is—

The design for a soap dish or bracket substantially as herein shown and described.

JOHN C. BUGH.

In presence of—

F. SIEGEL,
H. B. BRADSHAW.
